HOWARD J. MURRAY, OF BROOKLYN, NEW YORK, ASSIGNOR TO HENRY SIEBEN, OF HADLEY, NEW YORK

CUT-OFF VALVE

Application filed March 31, 1927. Serial No. 180,053.

The invention relates in general to a cut-off valve controlling mechanism of the type in which the closure is normally held by the mechanism in a preset open position, and 5 designed to be closed through the mechanism either by manual actuation from a remote point or automatically through a rise in temperature in the vicinity of the mechanism.

The primary object of the invention is to 10 provide an extremely simplified form of gas cut-off of the type outlined in which the number of structural parts have been reduced to a minimum; in which damaged or worn parts can be readily replaced without difficulty and 15 without necessity of using special tools to effect the substitution and in which ready access is provided for inspection and test.

In valves of this type now in general use 20 there is a tendency in those cases where the valve is moved by spring pressure into closed position engaging its seat that the valve frequently springs back off its seat with the result that the valve chatters back and forth before closing and this ineffective closing be- 25 comes more pronounced in those situations where the valve or its seat becomes worn through use or through the corrosive action 30 of the fluids passing the valve. It is known in the prior art to provide for certain ac- curate adjustments for the valve to insure an accurate seating of the same but these de- 35 vices are commonly in use for years without being actuated and the leakage past the valve does not become known until the emergency which required the closing of the valve occurs.

Accordingly, another object of the invention 40 is to provide for the closing of the valve positively and instantaneous, without possi- 45 bility of rebound, and to effect the complete closing of the valve on to its seat irrespec- tive of wear between the valve and its seat and independent of any nicety of adjustment of the valve relative to its closed position.

Still another object of the invention and 45 incidental to the desideratum to provide parts which can be readily replaced, is to provide a valvular unit including the valve per se, its mounting stem and actuating lever arm as a 50 single article free of springs so that the unit

or its component parts can be easily dismount- ed for repairs, for regrinding of the valve or readjustment of the actuating lever, without necessity of demounting any spring held parts which are usually difficult to manipu- 55 late.

Broadly, this phase of the invention is at- tained by mounting the valve closing spring as a part not physically connected in any way to the valvular unit and which operates 60 on the valvular unit simply by pressure bearing against one side of an actuating arm.

Still another object of the invention is to 65 provide a simplified form of fusible link con- nector for holding the valve in open position and which fusible link connector and its as- 70 sociated mountings are designed so as to per- mit an easy mounting of the connector in op- erative position in the act of replacing a new fuse for a damaged one.

Another object of the invention is to pro- 75 vide a simple and easily actuated means for releasing the fusible link from a distant sta- tion in releasing the valve to permit it to move under spring tension into its closed position.

Various other objects and advantages of 80 the invention will be in part obvious from an inspection of the accompanying drawings and in part will be more fully set forth in the following particular description of one form of mechanism embodying my invention, and the invention also consists in certain new and novel features of construction and com- 85 bination of parts hereinafter set forth and claimed.

In the accompanying drawings:

Fig. 1 is a view largely diagrammatic of a 90 valve constituting a preferred embodiment of the invention and showing the parts in their normal position with the valve held open;

Fig. 2 is a view similar to Fig. 1 showing 95 the valve in closed position after it has been released by the manual control from a re- mote station; and

Fig. 3 is a plan view of the device shown 100 in the preceding figures with the valve con- trol mechanism and its containing casing

shown in horizontal section taken on the line 3—3 of Fig. 1.

In the drawings and referring first to Fig. 3, there is shown a valve casing 10 provided with a seat 11 designed to be closed by a valve 12 and which valve is mounted on a rocking arm 13 secured to a valve stem 14 rotatably mounted in bearing 15 forming part of the casing 10 as is usual in such structure. Secured to the bearing 15 is a mechanism containing casing 16 having an open front closed by a gate or cover 17. The stem 14 projects into the interior of the casing 16 and has secured thereto two bell crank levers 18 and 19. The lever 18 is secured to the stem 14 by means of a key 20 so as to rotate therewith as the valve is moved to and from its seat. One arm 21 of the lever 18 is relatively long, normally depends from the stem 14 as shown in Fig. 1 and will be referred to hereinafter as a valve arm. The sides 22 of the valve arm opposite the valve seat 11 constitutes a bearing surface adapted to be engaged by a spring pressed actuating arm or cam and will therefore be referred to as a cam surface.

The other arm 23 of the lever 18 is provided adjacent its outer end with a laterally extending pin 24 for engaging in the eye at one end of a flat replaceable connector 25 formed of an easily meltalbe material and referred to hereinafter as a fuse link. The opposite end of the link 25 is provided with an eye 26 engaging a fixed stud 27 mounted on a block 28 secured to the rear wall 29 of the casing 16. From this disclosure it is seen that the valve is held normally in open position by means of the link 25 engaging the lever 18 at one end and in turn held rigidly in place relative to the casing by the engagement of its other end with the stud 27.

The valve is moved into closed position engaging its seat by means of a spring actuated locking arm or cam 30 loosely pivoted on a stub shaft 31 extending into the casing 16 from the rear wall 29. The free end of the arm 30 is provided with a camming finger 32 which bears on the cam surface 22 to move the arm 21 of the lever 18 from the position shown in Fig. 1 into the locked position shown in Fig. 2. A long powerful spring 33 has one end 34 bearing on a nut 35 forming part of the bearing 15, has its intermediate portion coiled about the stub shaft 31 and its other end 36 bearing on the arm 30.

From this construction, it is noted that normally the point of contact 37 between the arms 21 and 30 is on one side of a line *a—b* connecting the axes of rotation of the arms, and that this point is on the opposite side of the line from the valve seat. In its closing movement, the arm 30 exerts a camming action on the valve arm 21 with the point of contact 37 rotating clockwise about the cylindrical surface of the camming finger 32 and moving with a reciprocating movement

along the cam surface 22. Further the point of contact moves from one side to the other across the axis line *a—b*, the movement being intercepted by the engagement of the valve with its seat. As the arm 30 moves towards its final position shown in Fig. 2 it tends to approach a position at right angles to the length of the arm 21 and which position approaching ninety degrees of angle, will be referred to hereinafter as a high angle.

As the arms 30 and 21 assume this high angle any tendency of the valve to reverse its closing movement will be resisted by the mechanical lock provided by the rigid, strong arm 30. Opening strains originating in the valve will be transmitted along the length of the relatively short arm 30 and transferred directly to the rigid support provided by the stub shaft 31. As the arms approach the limits of the high angle the holding effect of the locking arm 30 increases according to the same law and the final locking effect is substantially independent of the tension of the valve closing spring 33.

It will be noted from the showing in Fig. 2 that there is the possibility of a further slight anti-clockwise movement of the arm 30 before it would leave the cam surface 22. This further movement compensates for any inaccuracies in the position of the closed valve relative to its seat and insures the movement of the valve on to its seat without necessity of any accurate adjustments of the valve. It is suggested that the cam surface 22 be laid out so as to insure a powerful final closing movement of the valve in spring, pressed and mechanically locked engagement with its seat.

The lever 19 has one arm 38 provided with a bifurcated wedge 39, beveled end forks 40 of which are adapted to be moved from the inoperative position shown in Fig. 1 into position straddling the fixed fuse supporting stud 27 as shown in Fig. 2. During this movement the beveled ends wedge the adjacent end of the fuse link off the stud 27 and thus permits the valve to close under action of the spring pressed arm as above outlined.

The other arm 41 of the lever 19 has a flexible connector 42 attached thereto as particularly shown in Fig. 3, and extends through a collar 43 on top of the casing 16 to a remote control station as is usual in devices of this character.

In operation the device functions as is usual in such constructions; the melting of the fuse 25 permits the spring 33 to overcome the tension of the spring 44 to force the valve into closed position and eventually into the mechanically locked position shown in Fig. 2. The melted fuse is replaced by a fresh fuse as shown in Fig. 2 and the device is ready for resetting with the new fuse holding the valve in open position as shown in Fig. 1.

Should it be desired to close the valve by

5 manual actuation a pull on the cable 42 causes the fork to release the fuse from its securing pin 27 and the valve closes as previously described when released by the melting of the fuse. For the purpose of holding the levers 18 and 19 in their normal position and with the link tripping fork in inoperative position as shown in Fig. 1, a relatively light spring 44 is coiled about the outer 10 end of the stem 14, has one end engaging the lever 19 as shown in Fig. 3 and has its other end bearing on a stud 45 extending laterally from the side of the lever 18.

15 While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

20 Having thus described my invention, I claim:

25 1. In a device of the class described, the combination of a mechanism containing casing, a valve stem rotatably mounted in the casing and protruding into the interior thereof, two levers mounted on the protruding end 30 of said stem, one of said levers fixed to the stem, means engaging said last named lever for holding the valve stem in a preset position, said means including a fusible link connecting the lever with the casing, the other 35 lever provided with wedging means for releasing the link from the casing, manually actuated means operable from a position exterior of the casing for moving said wedging means into operative position and spring controlled means in the casing for rotating the 40 stem when so released.

45 2. In a device of the class described, the combination of a fixed support, a valve provided with a stem, a bell crank lever secured to the stem, means acting on one arm of the lever tending to close the valve, a connector between the other arm of the lever and said fixed support to hold the valve in open position, and a manually actuated releasing lever 50 provided with wedging means for releasing the connector from said fixed support.

55 3. In a device of the class described, the combination of a support, a pin fixed to the support, a valve, means tending to move the valve on to its seat, means including a fusible link engaging said pin and the first mentioned means for holding the valve off its seat and a wedge having a bifurcated end movable 60 into position to straddle the pin and wedge the link off the same thereby to permit the valve to close, and a spring normally acting on said wedge to hold the same in an inoperative position and manually actuated means 65 operatively connected to said wedge to move

the same into its link releasing position against the tension of said spring.

4. In a device of the class described, the combination of a support, a pin fixed to the support, a valve, means tending to move the valve on to its seat, means including a fusible link engaging said pin and the first mentioned means for holding the valve off its seat and a wedge having a bifurcated end movable 70 into position to straddle the pin and wedge the link off the same thereby to permit the valve to close.

5. In a device of the class described, the combination of a valve provided with a stem having a valve arm, means engaging said arm and tending to move the valve into closed position, a fuse link for securing the valve in open position and a releasing lever pivotally mounted on the stem for releasing the fuse link and thus permit the valve to close. 80

6. In a device of the class described, the combination of a valve and its seat, said valve provided with a valve arm mounted for rocking movement, a rigid locking arm mounted for rocking movement about a fixed axis, 90 having its free end in bearing engagement with the valve arm and tending to move said arm to its valve closing position and to lock it in such position, and disposed to resist along its length the strains incidental to any tendency of the valve to move off its seat, and releasable means for normally holding the valve in open position. 95

7. In a device of the class described, the combination of a valve and its seat, said valve provided with a valve arm mounted for rocking movement, a spring actuated arm mounted for rocking movement about a fixed axis and bearing on the valve arm and tending to move said arm to its valve 100 closing position and to lock it in such position, said arms when the valve is in open position extending from their respective axes to one side of a line connecting said axes and movable past said line during their valve closing movement into a valve locking position on the opposite side of said line, and releasable means for normally holding the valve open. 105

8. In a device of the class described, the combination of a valve and its seat, spring actuated mechanism tending to close the valve on to its seat, said mechanism including locking means for securing the valve on its seat with a wedging action held against rebound, and for automatically advancing the valve into seating engagement as the contacting surface between the valve and its seat wears away. 115

9. In a device of the class described, the combination of a valve provided with a valve arm, having a cam engaging surface, a pivotally mounted cam bearing on said surface and tending to force the valve towards and eventually into locked engagement with its seat 125 130

and releasable means for normally holding the valve in open position.

10. In a device of the class described, the combination of a valvular unit including a valve and free of springs, a spring actuated locking device bearing on the unit and tending to move the valve into closed position and for securing the same locked in such position and releasable means for normally holding the valve open.

10 11. In a device of the class described, the combination of a valve control including means for holding the valve in open position, manually actuated means for releasing the holding means, spring actuated means acting on said control for moving the valve towards its closed position when said holding means is released, said spring actuated means providing a camming action for wedging the valve on to its seat.

20 12. In a device of the class described, the combination of a valve, releasable means for holding the valve open, an arm for moving the valve on to its seat, a pivotally mounted locking arm disposed to one side of said arm and bearing on the same and tending to close the valve and adapted when the valve is closed to extend from said arm at a high angle to lock the valve mechanically on to its seat.

30 Signed at New York, in the county of New York and State of New York, this 24th day of March, A. D. 1927.

HOWARD J. MURRAY.
